UNITED STATES PATENT OFFICE.

ROBERT W. JOHNSON, OF NEW BRUNSWICK, NEW JERSEY.

BANDAGE.

SPECIFICATION forming part of Letters Patent No. 700,938, dated May 27, 1902.

Application filed March 1, 1902. Serial No. 96,289. (No model.)

To all whom it may concern:

Be it known that I, ROBERT W. JOHNSON, a citizen of the United States, residing at New Brunswick, in the county of Middlesex and 5 State of New Jersey, have invented certain new and useful Improvements in Bandages, of which the following is a specification, reference being had therein to the accompanying drawings.

10 This invention relates to surgical bandages, and is particularly suitable as a catamenial bandage.

The objects of my invention are to produce an inexpensive bandage having in its interior 15 a series of flattened coils or layers of cobwebby rumpled cellulose tissue or paper and above said layers a thicker layer of absorbent cotton and under the layers of cellulose tissue or paper a thick layer of natural or non- 20 absorbent cotton, the whole retained connected together with gauze textile, as illustrated in the accompanying drawings, in which—

Figure 1 represents a perspective view of a portion of a bandage constructed in accordance with my invention, said portion being 25 cut off a short distance from one end of the bandage, the component parts thereof being cut off in the form of steps to show a portion of the surface of each material. Fig. 2 is a 30 transverse section of the same on a slightly-larger scale.

In said drawings the numeral 2 represents 35 a series of superposed flattened coils or layers of cobwebby rumpled cellulose tissue or paper obtained from wood-pulp mixed with hot water and made to pass on a sieve and around cylinders in a very thin sheet, where it is partly dried and then scraped therefrom. The production of said rumpled cellulose-paper 40 and its nature are fully described in United States Patent No. 468,480, dated February 9,

1892. Although said cellulose tissue-paper is very soft and flexible, sheets of it rubbed together do not become matted, as carded wood-pulp or cotton fibers are liable to be, 45 and it has enough cohesion to retain its form even when subjected to friction, and this is of importance in catamenial bandages. Upon this rumpled cellulose tissue or paper 2 is placed a layer of absorbent cotton 3 of a 50 thickness equal to about three or more of said paper, and under it a layer of non-absorbent cotton 4 as obtained directly from the seed and slightly thicker than the layer of absorbent cotton, and the whole is inclosed in a 55 strip of gauze textile, as cheese-cloth, of such width that its edges will overlap each other a sufficient distance to protect the component parts of the bandage against displacement when in use. 60

Having now fully described my invention, I claim—

1. An absorbent bandage consisting of series of layers of rumpled cellulose tissue or paper, a thicker layer of absorbent cotton 65 above said rumpled paper, another thick layer of non-absorbent cotton under said rumpled paper, and a textile covering inclosing all the layers, substantially as described.

2. An absorbent bandage consisting of series of layers of rumpled tissue-paper, a layer of absorbent cotton above said paper, a layer of non-absorbent cotton under said rumpled paper, and a covering inclosing all the layers, substantially as described. 70

In testimony whereof I affix my signature in presence of two witnesses.

ROBERT W. JOHNSON.
